UNITED STATES PATENT OFFICE.

WALTER STUMPF, OF BALTIMORE COUNTY, MARYLAND, ASSIGNOR TO THE BLACK AND DECKER MANUFACTURING COMPANY, OF TOWSON, MARYLAND, A CORPORATION OF MARYLAND.

RIVET-SPINNING ATTACHMENT.

Application filed November 6, 1925. Serial No. 67,264.

The invention relates to an attachment in the nature of a special bit for a portable, power-driven, rotary tool of the type most generally used for drilling. These tools in 5 some instances more or less modified as to certain details, are also used for other purposes as screw-driving, nut and bolt setting, buffing, grinding and valve grinding.

The object of the present invention is to 10 provide means whereby a power-driven portable drill or screw-driver, etc., is immediately adapted for use in heading or setting rivets by spinning. The rivet spinning operation as performed in this way, the rivets 15 being most generally handled cold, consists in applying a moderate degree of pressure to the points of the rivets in the direction tending to upset and head them, at the same time rotating the pressing member at a high 20 speed, so that the pressing tool, being cup-shaped, the metal forming the rivet end or point, is caused to flow laterally and assume a convex form corresponding to the shape of the inside of the cup.

25 Stationary rivet spinning machines are quite generally used. In the manufacture of automobile bodies and other comparatively bulky sheet metal products, small rivets are driven in large numbers and headed cold. 30 These cannot be conveniently set by means of a stationary machine on account of the difficulty in handling the article which is being manufactured and have therefore been set by hand with a hammer. The spinning 35 operation can be performed by a workman having less skill and is much neater, quicker and more uniform, and with the present attachment, any portable, power-driven, rotary tool of the general type referred to can 40 be used for this purpose.

The attachment comprises a spindle or bit adapted to be inserted in the chuck of the rotary tool, and is equipped at its lower end with a spinning tool and a work support. 45 The spindle carries a laterally extending guiding block or bearing member mounted thereon, the spindle being in effect mounted to rotate in a suitable bearing in said member. The work support or anvil is aligned 50 with the rivet-spinning tool, and carried by a sliding bar mounted in a slide bearing in said block or bearing member parallel to the spindle bearing. The sliding bar is actuated by a hand lever by the operation of

which the anvil is pressed upward against 55 the work; in other words, the anvil is caused to approach the spinning tool whereby the rivet head being engaged by the anvil, the rivet is compressed between the spinning tool and the anvil, and the tool being then 60 rotated, the spinning operation is performed.

In the accompanying drawing I have illustrated a rivet spinning attachment embodying the features of my invention in the preferred form. 65

In the drawing—

Figure 1 is a full size view of the attachment shown in front elevation.

Figure 2 is a top plan of the same.

Figure 3 is a fragmentary elevation looking from the left in Figure 1, the handle lever being shown in section on line 3—3 Figure 1.

Figure 4 is an elevation looking from the right in Figure 1. 75

Figure 5 is a view on a reduced scale showing an electric drill equipped with the attachment of the invention.

Referring to the drawings by numerals, each of which is used to indicate the same 80 or similar parts in the different figures, the illustration includes a portable, power-driven, rotary tool 1, the tool illustrated being a small electric drill to which the rivet-spinning attachment 3 is connected by 85 chuck 2.

The rivet-spinning attachment consists of the spindle 4, anvil or work support 5 and bearing block 6, and is provided with parallel bearings consisting of a rotary bearing 90 7 for the spindle 4 and slide bearing 8, in which latter is mounted the sliding bar 9 supporting the anvil 5. The rivet-spinning tool 11 is mounted on the lower end of spindle 4 and the anvil 5 is in alignment with 95 the tool in the direction of the spindle axis so that the traverse of the bar carries the anvil toward and from the spinning tool. The sliding bar is actuated by a toggle 12 controlled by hand lever 13.

100 The rotary spindle 4 is held in the bearing 7 by a collar 14 at the top, secured by means of a set-screw 15, and above the collar the spindle is provided with a reduced shank 16 adapted to enter and be secured 105 in the chuck 2. Below the bearing block 6 the spindle 4 is provided with a thrust bearing 17 which bears against the bottom face

of the block, and a shoulder 18 on the shank. The tool shank below the shoulder is in the form of a fork 19 in which is mounted the spinning tool 11 on a transverse pin 20, the 5 tool being shown as of the regular type now in use, consisting of a plurality of rollers forming together a concave peripheral surface 21 with a central slot or radial opening 22.

- 10 The sliding bar 9 as shown is rectangular and the bearing 8 is likewise rectangular and of similar dimensions to receive and fit the sliding bar. The latter is formed at its lower end with a transverse base bar 24 so that the 15 entire sliding member may be referred to as L-shaped. The anvil 5 is shown as having a threaded shank 25 seated in a threaded hole 26 in the end of the base 24 and directly in alignment with the axis of the spindle 4 and 20 with the spinning tool 11. The screw-shank 26 has a suitable head 27 and is held in adjusted position by a lock nut 28.

The toggle 12 comprises a link 29 pivotally connected at 30 to the bearing block 6, and 25 also pivotally connected at 31 at its upper end to the hand lever 13, the pivot end of which 32 forms the second link of the toggle being otherwise pivoted at 33 to the sliding bar 9. The two pivot points 31 and 32 on the handle 30 lever link are spaced apart a distance corresponding to the length of the other link 29. The link end 32 of the hand lever is seated in a slot 34 in the block which enters the bearing cavity 8 and exposes the sliding bar. 35 The bearing cavity 8 is open at the left in Figure 1, the opening being covered by a cover plate 35 held by screws 36.

The operation of the rivet spinning tool will be fully understood from the description and preamble. The drill or similar tool in connection with which it is used and by which it is operated may be used for the various purposes to which it is adapted as drilling, screw-driving, grinding, buffing or the like, the attachment herein described being no more than a special bit which can be removed and set aside with the other equipment of the tool and used when desired. With this attachment the portable drill or similar tool becomes adapted for use in spinning or heading rivets particularly small rivets which are set cold though it may be adapted for hot riveting, the work produced being neater and more uniform and quicker, cheaper and more economical than can be produced by hand or with stationary machines, the use of stationary machines with large work being inconvenient, slow and comparatively expensive.

I have thus described specifically and in 60 detail a rivet spinning attachment embodying my invention in the preferred form in

order that the nature and operation of the same may be clearly understood; however, the specific terms herein are used descriptively rather than in their limiting sense, the 65 scope of the invention being defined in the claims.

What I claim and desire to secure by Letters Patent is:

1. A rivet spinning attachment for a portable, power-driven, rotary tool, the attachment consisting of a spindle having one end adapted to be connected to a rotary portion of the tool the other end being adapted to support a rivet spinning bit, a work support, 70 a sliding bar on which said support is mounted in alignment with the spindle, a bearing for the sliding bar parallel to the spindle, means including a thrust bearing mounted on the spindle supporting said bearing for the sliding bar, and means for actuating the sliding bar to compress the rivet between the work support and the tool.

2. A rivet spinning bit for a portable power-driven tool or other hand tool comprising 85 a spindle having at one end a shank adapted to be engaged by a bit chuck and at the other end a rivet spinning tool, an anvil supported by the spindle in alignment with the rivet spinning tool, and means for moving the anvil toward the tool to compress a rivet between the tool and the anvil.

3. A rivet spinning bit comprising a shank adapted to be engaged by a bit chuck, a rivet spinning tool carried by and connected to 95 said shank to be rotated thereby, a work support also carried by the shank and means for controlling the relative position of the work support and bit whereby a rivet may be compressed between the rivet spinning tool 100 which is applied to the point of the rivet and the work support which is applied to the head of the rivet.

4. A rivet spinning bit for a portable rotary tool, the bit having a shank adapted for connection with a rotary portion of the tool, a rivet spinning tool connected to said shank to be rotated thereby, a guide, means supporting the same on the shank, a sliding bar mounted therein to move parallel to the axis 110 of said rotation of the rivet spinning tool, an anvil carried by the sliding bar in alignment with the spinning tool in the direction of the said axis thereof, and means carried by the bit for actuating the sliding bar to cause the anvil to approach the tool whereby the tool being applied to the point of the rivet and the anvil to the head, the rivet may be compressed between the tool and the anvil.

Signed by me at Baltimore, Maryland, this 120 3 day of November, 1925.

WALTER STUMPF.
